TIE PLATE

Filed Nov. 10, 1930

INVENTOR

Richard E. Bell

By J. Henry Tinealy
ATTORNEY

UNITED STATES PATENT OFFICE

RICHARD E. BELL, OF ST. LOUIS COUNTY, MISSOURI

TIE PLATE

Application filed November 10, 1930. Serial No. 494,589.

My invention relates to tie plates such as are commonly used to support railroad rails.

Tie plates heretofore used have been of substantially the same thickness throughout their length although, of course, tie plates of the compression type have had the bottoms thereof recessed to form compression ribs or grooves. If a tie plate is made of substantially the same thickness throughout its length an unnecessary amount of metal must be included therein because the parts of the plate carrying a very little load are made just as heavy as the parts of the plate carrying the comparatively great load of the rail and any weight imposed thereon. Such plates are needlessly expensive in manufacture because of this unnecessary amount of metal included therein. However, I have found that a tie plate embodying my invention as set forth below may be made strong and rugged and yet be much lighter and, therefore, much less expensive than the tie plates heretofore used.

The object of my invention is to provide a tie plate in which the metal is distributed in the various parts thereof according to the load carried thereby and according to the strains imposed thereon.

With this and other objects in mind several embodiments of my invention are shown in the accompanying drawings wherein similar characters are used to designate similar parts: Fig. 1 is a section of a tie plate embodying one form of my invention; Fig. 2 is a top view of the tie plate shown in Fig. 1; Figs. 3 and 4 are sections of modified forms; Fig. 5 is an end view of the forms shown in Figs. 1, 2 and 3; and Fig. 6 is a cross section along the lines 6-6 of Fig. 4.

Referring to the drawings and particularly to Figs. 1 and 2 the form of tie plate 1 shown therein as embodying my invention has a pair of transversely arranged members 2 positioned so as to receive on the top part thereof the marginal surfaces of the flange of a rail to be carried by the plate. The top of the plate 1 has a recessed portion 3 between transverse members 2 and recessed portions 5 at each end of the plate therebeyond. In the recessed portion 3 are a plurality of lon-

gitudinally extending reinforcing ribs 4 and in the recessed portions 5 at the ends of the plate are a plurality of reinforcing ribs 6. The reinforcing ribs may be of any shape, but I prefer that they have gradually sloping walls as shown in Fig. 5. I also prefer that the upper ends of the ribs 4 terminate below the parts of the transverse members 2 adapted to receive the rail flange. Likewise, I prefer that the ribs 6 in the recessed portions 5 are reduced in height towards the ends of the plate so as to merge substantially into the bottom of the recessed portions 5, all as clearly shown in the figures. A shoulder 7 may be provided on one of the transverse members 2 to engage the edge of the rail flange and the plate may be provided with the usual spike holes 9. Each of the transverse members 2 may have a short rib 8 depending therefrom and otherwise arranged to be forced into the tie sufficiently to hold the plate in position while the rail is being laid and spiked.

In the form of my invention shown in Fig. 3 the top of the tie plate has recessed portions only at the ends thereof beyond the transverse members 2. However, the bottom of the tie plate has a recessed portion 10 between the transverse members 2 in which is formed a plurality of compression ribs 11 arranged to form compression grooves between adjacent ribs. In the form of my invention shown in Fig. 4 the tie plate has the recessed portions 3 and 5 and the reinforcing ribs 4 and 6, as shown in Fig. 1, and in addition has the recessed portion 10 on the bottom thereof between the transverse members 2 and recessed portions 12 at the end of the plate therebeyond. However, compression ribs 11 are formed only in the recessed portion 10 on the bottom of the plate.

The use and action of a tie plate embodying my invention is as follows: In each form shown the transverse members 2 extend from top to bottom of the plate so as to form in effect a pair of strong bars upon which the rail is supported on the tie. These transverse members, of course, must be heavy enough to carry the load. When the tie plate is put into position if the short transverse

ribs 8 are provided on the bottom of the members 2 these ribs may be forced into the tie sufficiently to hold the plate in position until the rail is laid and the spikes are driven.

5 When the rail is secured in place if the form of tie plate embodying my invention shown in Fig. 4 is used the lower parts of the transverse members 2 will initially seat on the tie, as described in my previously issued Patent No. 1,719,644 dated July 2, 1929, but as trains pass over the rail they will be forced into the tie and the fibres of the tie between the members will be compressed in the recessed portion 10 by the compression ribs 11.

10 15 I prefer, as stated above, that the reinforcing ribs 4 in the middle recessed portion 3 in the top of the plate terminate below the part of the transverse members 2 which engage the rail so that none of the weight of 20 the rail or the load imposed thereon will be carried directly by the middle of the plate.

It will be noted that in any of the embodiments of my invention shown the strength of the load carrying portions of the 25 plate has not been diminished, but the portions of the plate which carry only a small load have been reduced in size so that the weight and consequent manufacturing cost of the plate are greatly reduced.

30 35 I do not intend to limit my invention to the exact details of structure shown in the drawings because, although I have shown three embodiments of my invention, tie plates in modified forms may be made in a variety of shapes, sizes, and arrangements of the parts without deviating from the spirit of my invention as included in the claims set forth below.

40 45 What I claim as new and desire to secure by Letters Patent, is:—

1. A tie plate having a part at the top thereof arranged and adapted to receive a rail flange, said plate having recessed portions at each end of the top thereof beyond said part and a plurality of longitudinally extending reinforcing ribs in said recessed portion.

50 55 2. A tie plate having a pair of transversely arranged members adapted to receive the marginal surfaces of a rail flange, said plate having recessed portions in the top thereof between said members and at each end of said plate therebeyond, and a plurality of longitudinally arranged reinforcing ribs in each of said recessed portions.

60 65 3. A tie plate having a pair of transversely arranged members extending from top to bottom of said plate and having their upper parts adapted to receive the marginal surfaces of a rail flange, and said plate having recessed portions in both the top and bottom thereof between said transverse members and at each end of said plate therebeyond.

70 75 4. A tie plate having a pair of transversely arranged members extending from top to

bottom of said plate and having their upper parts adapted to receive the marginal surfaces of a rail flange, said plate having recessed portions at both the top and bottom thereof between said transverse members and at each end of said plate therebeyond and a plurality of longitudinally arranged reinforcing ribs in said recessed portions in the top of said plate.

80 85 90 95 100 105 110 115 120 125 130 5. A tie plate having a pair of transversely arranged members extending from top to bottom of said plate and having their upper parts adapted to receive the marginal surfaces of a rail flange and having their lower parts adapted to initially seat on the tie, said plate having recessed portions at the top and bottom thereof between said transverse members and at each end of said plate therebeyond, a plurality of longitudinally arranged reinforcing ribs in said recessed portions in the top of said plate with the reinforcing ribs between said members having their upper ends terminating below the parts of said transverse members which receive the rail flange, and a plurality of compression ribs arranged in the recessed portion on the bottom of said plate between said transverse members.

In witness whereof I have signed my name to this specification.

RICHARD E. BELL.
